DESIGN FOR A SLICING MACHINE

Carroll E. Breaden, Dayton, Ohio

Application September 21, 1934, Serial No. 53,344

Term of patent 14 years

To whom it may concern:

Be it known that I, Carroll E. Breaden, a citizen of the United States, residing at Dayton, in the county of Montgomery and State of Ohio, have invented a new, original, and ornamental Design for Slicing Machines, of which the following is a specification, reference being had to the accompanying drawing, forming part thereof, in which—

Figure 1 is a front perspective view of the slicing machine showing also the left side thereof.

Figure 2 is a rear perspective view of the slicing machine showing also the right side thereof.

I claim:

The ornamental design for a slicing machine as shown.

In testimony whereof I affix my signature.

CARROLL E. BREADEN.
